UNITED STATES PATENT OFFICE

HUGH HARMAN AND RUDOLPH C. ISING, OF LOS ANGELES, CALIFORNIA

DESIGN FOR A DOLL

Application filed December 6, 1932. Serial No. 46,314. Term of patent 14 years.

To all whom it may concern:

Be it known that we, HUGH HARMAN and RUDOLPH C. ISING, both citizens of the United States, residing at Los Angeles, county of Los Angeles and State of California, have invented a new, original, and ornamental Design for a Doll, of which the following is a specification, reference being had to the accompanying drawing, forming a part thereof.

Figure 1 is a front elevation of the doll,

and

Figure 2 is a side elevation thereof.

We claim:

The ornamental design for a doll, as shown.

HUGH HARMAN.
RUDOLPH C. ISING.
